ABSTRACT: Method and means for securing thin-webbed metalwork on boiler or like housing wall, as for retaining insulation and/or finishing sheeting thereon. Studs may have inner ends welded to housing wall by use of a stud welder. Areas of metalwork strip impacted against reduced ends of studs to punch through web, and further impaction forms heads to retain metalwork against peripheral shoulders defined by reduced ends.

METHOD FOR INSULATING BOILER OR LIKE HOUSING WALL

BACKGROUND OF INVENTION

In the past the method generally employed for insulating a boiler wall, for example, included spot welding vertically spaced, Z-shaped metal strips to the wall to support sheet insulation material between them, and securing sheet finishing material to the Z-strips as by means of self-threading screws. This procedure was rather expensive in several respects, and the finished structure was subject to substantial heat loss conducted from the boiler walls to the sheet finishing material, through the entire lengths of the metal strips.

SUMMARY OF INVENTION

The method of the present invention has particular utility for retaining insulating material against a boiler wall, and includes welding rows of spaced metal studs on the wall to extend normal thereto, the studs having reduced outer ends defining annular shoulders adapted to be in given spaced relation to the wall, and said reduced outer ends being recessed to define a peripheral cutting edge. A channel-shaped strip of thin metal is supported to press a web portion thereof against the reduced ends of each said row of studs, while a mallet or other impacting tool is progressively struck against the web at the several points of contact thereof with cutting edges of the studs, first the punch holes through the web, and then to form or peen heads on the reduced portions for retaining the strip against the annular shoulders. A plurality of said channel strips attached in this manner, in parallelism to each other, may be used to support protective metal sheeting to outer flanges of the exposed webs of the channel strips, as by means of self-threading screws.

A general object of the invention is to provide an improved method and means for covering a boiler or like wall with insulating and finishing materials with a substantial reduction in time, labor, and material as compared with known prior art methods.

Other objects of the invention will be manifest from the following brief description and the accompanying drawings.

Of the accompanying drawings:

FIG. 1 is a fragmentary horizontal cross section through a boiler or like wall, illustrating an initial step in the method by which special studs are welded to the wall, a metal strip being shown, by chain-dotted lines, in position for attachment to the studs.

FIG. 2 is a fragmentary front elevation of the wall as shown in FIG. 1.

FIG. 3 is an enlarged vertical cross section, taken substantially on the line 3-3 of FIG. 2, but showing the metal strip in full lines, and held against a cutting edge on a reduced portion of a stud.

FIG. 4 is a fragmentary view corresponding to a portion of FIG. 3, and on the same scale, illustrating the metal strip pierced by the cutting edge of a stud, and held against a shoulder thereon by a retaining head formed on the reduced portion of the stud.

FIG. 5 is a fragmentary front elevation as viewed from the right of FIG. 4, and on the same scale.

Referring to FIGS. 1 to 5 of the drawings, generally, and to FIGS. 4 and 5 in particular, there is illustrated one application of the method and means of the present invention, as for insulating a boiler wall 10 with a layer 11 of molded or loose insulating material. Where the layer 11 is a molded insulating material it may be retained against the wall 10 by a plurality of thin-webbed, channel-shaped, metal strips 12, 12, each affixed to a row of spaced metal studs 13, 13 rigidly attached to metal wall 10. The strips 12, as best shown in FIG. 4, are adaptable for attaching corrugated metal or other protective sheeting C thereto, as by means of self-threading screws S (see chain-

dotted lines in FIG. 4).

Referring to FIG. 3, each stud 13 may comprise a length of metal rod stock which is flat at one end 15, and has a reduced neck portion 16 at the other end, defining an annular shoulder 17. The outer end of reduced portion 16 may be recessed or concaved at 18, as shown in FIG. 3, to define a sharp peripheral cutting edge 19, for purposes to be described.

In use of the method of the invention for insulating a boiler wall 10, for example, an insulating layer 11 of uniform thickness may be retained flatwise against the wall, as shown in FIG. 1, after a plurality of studs 13 have been welded to the wall 10, in known manner, to extend normal to the wall. As an example, a suitable welding tool may be applied over the reduced end 16 of each respective stud, and operated to pass a requisite electrical charge through and the stud to weld the flat end 15, thereof to the wall 10. Rows of spaced studs 13 are thus welded to the wall to have the annular shoulders 17 thereof uniformly spaced from the wall, to be substantially flush with the outer surface of the required insulating layer 11, as shown in FIG. 1.

Next, while a thin-webbed, metal channel strip 12 is held against the cutting edges 19 of a row of aligned studs 13, the web 21 of the channel strip is impacted by a mallet or other tool, at areas opposite each respective stud, first to punch a hole in the web 21, so that the strip can be forced inward of each location, to full engagement of the web with the annular shoulder 17 of the respective stud, and then with further impact against the respective protruding stud portion with a suitable impact tool, a head 22 is formed, as shown in FIGS. 4 and 5, firmly to secure the strip 12 against shoulder 17.

With a plurality of said channel strips 12 suitably mounted in parallelism to hold the insulation 11 against wall 10, the insulated area can be protected, as by a facing of decorative sheeting C, such as corrugated metal, secured to the strips 12 by self-threading screws S (see chain-dotted lines in FIG. 4).

Modifications of the invention may be resorted to without departing from the spirit thereof or the scope of the appended claims.

I claim:

1. A method for securing thin-webbed metalwork to an existing metal wall surface comprising: the steps of affixing to said wall surface a plurality of studs, each having a reduced free end portion defining a peripheral shoulder to be in spaced relation to the wall surface when the other end of the respective stud is secured thereto, and the outer end of said end portion being recessed to define peripheral cutting edge; supporting the metalwork to engage said thin web portion thereof against said cutting edge of each stud; and impacting said engaged web portion against the cutting edge of each stud; first to pierce and project the reduced portion thereof through the corresponding web portion, and then to peen the respective projected free end portion against the web portion, thereby to form heads on the respective studs for securing the web portion to the peripheral shoulder of the studs; and securing a facing of sheet material to said metalwork to form an enclosure between said wall and said facing sheet.

2. A method as in claim 1, each said stud being affixed to said wall surface by applying a welding charge therethrough while said other end of the stud is held against said wall, to weld the stud thereto.

3. A method as in claim 2, including retaining a filler of insulating material between the secured said web portions and said wall.

4. A method as in claim 1, including retaining a filler of insulating material between the secured said web portion and said wall.

5. A method as in claim 1, including retaining a filler of insulating material between the secured said web portion and said wall.
